UNITED STATES PATENT OFFICE

111,511

DESIGN FOR A SERVICING APPARATUS OR THE LIKE FOR FILLING STATIONS

Alexander P. Fox, University City, Mo., assignor
to Lincoln Engineering Company, St. Louis,
Mo., a corporation of Missouri

Application July 2, 1938, Serial No. 78,249

Term of patent 7 years

To all whom it may concern:

Be it known that I, Alexander P. Fox, a citizen
of the United States and a resident of University
City, St. Louis County, Missouri, have invented a
new, original, and ornamental Design for Servic-
ing Apparatus or the Like for Filling Stations, of
which the following is a specification, reference
being had to the accompanying drawing, form-
ing part thereof, in which

Fig. 1 is a front perspective view;

Fig. 2 is a side elevation; and,

Fig. 3 is a rear elevation of a servicing appa-
ratus for filling stations, showing my new design.

I claim:

The ornamental design for a servicing appa-
ratus or the like for filling stations, substan-
tially as shown.

ALEXANDER P. FOX.
